UNITED STATES PATENT OFFICE

2,488,261

SUBMARINE MASK FOR ATMOSPHERIC AND AUTONOMOUS BREATHING

Nerino Bedini, Milan, Italy, assignor to Pirelli Societa Per Azioni, Milan, Italy

Application September 12, 1947, Serial No. 773,703
In Italy February 1, 1947

7 Claims. (Cl. 128—145)

1

This invention relates to a submarine breathing device, and more particularly to a breathing mask which permits the wearer, while submerged, to breathe air from the atmosphere above the water, and in addition is provided with a supply of respiratory gas which he may use for breathing when submerged at depths below which the normal atmospheric air cannot be supplied.

Submarine masks are known, having an upwardly extending breathing tube which permits the wearer to breathe directly from the air above the water when he is submerged at a relatively shallow depth. In this type of device the upper end of the breathing tube is provided with a valve automatically operated by a float, to prevent the entrance of water into the breathing tube whenever its open end is submerged, and to allow the passage of air as long as the tube projects above the water. Thus the wearer may work submerged but he must return at intervals, depending upon his lung capacity, to a point near the surface of the water to breathe.

Submarine masks are also well known, having an air or oxygen supply carried at high pressure in a container or bottle strapped to the wearer's body, with a suitable means for feeding the gas from the container to the mask. This type of mask allows the wearer great freedom of action while submerged, while the length of time he may remain submerged is limited only by the capacity of the gas supply. However, the submersion time can be increased still more if a mask of the type having an independent respiratory gas supply is also provided with a means for allowing the wearer to breathe the surface air when he is submerged at shallow depths, while conserving the supply of gas in the container.

Therefore, an object of this invention is to provide a submarine mask, whereby the wearer to remain submerged for periods of relatively long duration, characterized by the fact that it is combined with automatically operated means for permitting the wearer to breathe from the atmosphere while yet submerged, together with means to supply the wearer with a respiratory gas when the atmospheric air supply is withdrawn.

Another object of the invention is to provide a submarine mask permitting the wearer to remain submerged for periods of relatively long duration and characterized by the fact that it is provided with a respiratory gas supply for use when the wearer is submerged at relatively great depth, and means automatically operated whereby, when the gas supply is cut off, the wearer may

2

breathe air from the atmosphere while submerged at relatively shallow depths.

The above and additional structural features and advantages are explained in detail in the following specification and are illustrated in the accompanying drawing, in which:

Figure 1 is a view of the device as worn by a diver;

Figure 1A is a detail view of the device for manually controlling the air and gas supply;

Figure 2 is a left side view of the mask as worn, showing a portion of the breathing tube, and the float valve, in cross-section; and

Figure 3 is a perspective view of the lung bag.

Referring now to the drawing in detail, the face piece of the mask is indicated by the reference numeral 1. This is made of a pliable, waterproof material such as rubber and is shaped to extend over the top and a portion of the back of

the head. Straps 1a are adjusted by means of buckles 1b to keep the face piece in place. The face piece 1 also extends downwardly under the chin and fits snugly so that the wearer may breathe without getting water in the eyes and

nostrils. A window 1c, of transparent material, such as glass, is fitted into the front portion of the face piece. Secured to an opening in lower front portion of the face piece is a coupling 2. A mouthpiece 7 is connected to this coupling by a short length of flexible tubing (not shown) on the inside of the mask. Connected to the coupling 2 on the outside of the mask, is the three-way valve 2. The breathing tube 3 for atmospheric air, and the flexible hose 16 communicating with a storage bag 4, are also connected to the three-way valve 2. The construction of this valve may be of any conventional design, containing a core which may be rotated by the handle 13 so that in one position a passage is formed

between the breathing tube 3 and the mouthpiece 7, and in the other position a passage is formed between the hose 16 and the mouthpiece 7.

The bag 4 is hereinafter termed a lung bag, so called because it is used to store gas to be breathed, and may be made of any pliable waterproof material, such as rubber. It is shaped somewhat in the shape of an inverted truncated pyramid with the small end down, permitting it to conform generally to the shape of the wearer and to allow free movement of the wearer's arms. Furthermore, by shaping the lung bag 4 in this manner the weight of the gas container, which is supported by the lung bag 4, is more evenly distributed. A strap 21 fits around the wearer's neck and is adjustably attached to the lung bag 4

3

by means of the buckles 20. When in position the lung bag 4 is worn over the chest as shown in Fig. 1. Another strap 23, provided with the adjustable buckle 23a, is attached to the lower portion of the lung bag 4, and fits around the waist to keep the lung bag 4 from swinging away from the body when the wearer is inclined in a forward position. A container 5 for a respiratory gas such as oxygen is supported in a sling having two straps 22, attached to the bottom of the lung bag 4 and which straps are adapted to encircle the container 5. The container 5 may be a conventional metal cylinder, or bottle, commonly used for compressed gases, and is provided with an adjustable regulator valve 6 of the usual type. The tube 18 connects the outlet from the valve 6 to the inlet port of the lung bag 4. If oxygen is supplied to the lung bag 4, a purification cartridge 17 may be positioned inside.

The breathing tube 3, which may be made of any rigid material, extends upwardly from the three-way valve 2, and backwardly to a point a short distance behind the wearer's head, so that when he is floating submerged at a shallow depth, facing the bottom, the upper end of the breathing tube 3 will project above water. The upper end of the breathing tube 3 is provided with an automatically operated valve device 9 and 24, to permit air to pass into the breathing tube when the upper end of the tube is above water but which, before the end of the tube becomes submerged, will close off the passage to prevent the entrance of water. Conversely, when the upper end of the tube 3 emerges into the air from a submerged position, the air passage is automatically re-opened. This valve device, 9 and 24, is the subject matter of a co-pending application, Serial No. 770,796, filed August 27, 1947, and forms no part of this invention. The device comprises a bell-shaped spray shield 24 having a substantially flat lower portion 24a, provided with a number of openings 24b to permit air to enter the spray shield. The float 9 is provided with a hole through its central portion to allow it to be slidably positioned on the breathing tube 3. A stop 9a limits downward movement of the float when out of water, but when the device is submerged the buoyancy of the float pushes it up against the flat portion 24a of the spray shield, thus closing the openings 24b, as shown by the dotted lines in Fig. 2. A drainage valve 19 is provided in the lower portion of the breathing tube.

The upper end of the breathing tube 3 is provided with a plug 10 shaped to close the end of the tube. Normally the plug is supported a short distance away from the end of the tube by a coil spring 14 attached, as by spot welding, to the inside of the tube 3. A wire 11 is attached to the center of the plug 10. At a point above the three-way valve 2 a hollow tube 15 is joined to the breathing tube 3. The tube 15 extends inwardly and downwardly toward the three-way valve 2. The wire 11 is carried on the inside of the breathing tube 3 for a portion of its length until it reaches the point where tube 15 joins breathing tube 3. From this point the wire 11 is carried by the tube 15. The lower end of tube 15 is provided with a packing gland 15a, through which the wire 11 passes. This packing gland allows the wire to be pulled to operate the plug 10, but prevents entrance of water into the tube.

Projecting from the side of the three-way valve 2 away from the handle 13 is a shaft 2a which is attached to the core of the valve concentric

with its axis of rotation. Attached to this shaft is an arm 12. The wire 11 is pivotally attached at 12a to the end of the arm 12. The arm is positioned so that when the three-way valve is in the position to admit air from the breathing tube 3 into the mouthpiece 1, the arm will be in the position shown by the solid lines in Fig. 1A, and the plug 10 will be held away from the upper end of the breathing tube by the spring 14. When the three-way valve is rotated by the handle 13 to the position shown by the dotted lines in Fig. 1A, the mouthpiece 1 will be connected to the flexible hose 18, and the arm 12 will pull the plug 10, by means of the wire 11, into engagement with the end of the breathing tube 3.

From the foregoing, it will be clear that the breathing device described and illustrated herein is adapted to enable a submarine worker to remain submerged for relatively long periods of time. While the worker is so engaged he may be located at considerable depths while his supply of gas is sufficient, and he need not return to the surface to obtain fresh air but only close enough to enable the upper end of the air tube to project above the surface of the water.

I claim:

1. A submarine breathing device comprising a face mask, a mouthpiece, an upwardly extending breathing tube, a container for respiratory gas, means to connect either said breathing tube or said container to said mouthpiece, a spray shield attached to the upper end of said breathing tube, a valve within said shield and adapted to open or close the upper end of said tube under the control of said means, an opening provided in the lower portion of said spray shield to allow the passage of air into the tube, and a float provided with a hole therethrough permitting it to be slidably positioned on said breathing tube below the opening in said spray shield, a portion of said float cooperating with said opening to prevent the entrance of water into said breathing tube when the float is submerged.

2. A submarine breathing device comprising a face mask, a mouthpiece, an upwardly extending breathing tube, a container for respiratory gas, a lung bag shaped in the form of an inverted truncated pyramid, means to support said lung bag over the chest of the wearer, means to support said respiratory gas container from the bottom of said lung bag, means to conduct gas from said container to said lung bag, means to connect either said breathing tube or said lung bag to said mouthpiece, a spray shield attached to the upper end of said breathing tube, a valve within said shield and adapted to open or close the upper end of said tube under the control of said means, an opening provided in the lower portion of said spray shield to allow the passage of air into the tube, and a float provided with a hole therethrough permitting it to be slidably positioned on said breathing tube below the opening in said spray shield, a portion of said float cooperating with said opening to prevent the entrance of water into said breathing tube when the float is submerged.

3. A submarine breathing device comprising a face mask, a mouthpiece, an upwardly extending breathing tube, a container for respiratory gas, a three-way valve, means to connect said mouthpiece, breathing tube and gas container to said three-way valve so that by manipulation of the operating handle of said valve the mouthpiece 70 may be connected either to said breathing tube

or to said gas container, a spray shield attached to the upper end of said breathing tube, an opening provided in the lower portion of said spray shield to allow the passage of air into the tube, a float provided with a hole therethrough permitting it to be slidably positioned on said breathing tube below the opening in said spray shield, a portion of said float cooperating with said opening to prevent the entrance of water into said breathing tube when the float is submerged, a plug within said spray shield adapted to close the upper end of said breathing tube, resilient means normally urging said plug away from the end of said tube, and means connecting said plug and said three-way valve so that when the mouthpiece is connected to the gas container said plug will close the upper end of said breathing tube.

4. A submarine breathing device comprising a face mask, a mouthpiece, an upwardly extending breathing tube projecting above said mask and through which air may be admitted, a container for respiratory gas, a three-way valve, a single control element for said valve, means to connect said mouthpiece, breathing tube and gas container to said three-way valve so that by manipulation of the control element of said valve the mouthpiece may be connected either to said breathing tube or to said gas container, a plug adapted to close the upper end of said breathing tube, resilient means normally urging said plug away from the end of said tube, and means connecting said plug and said three-way valve so that when the mouthpiece is connected to the gas container said plug will close the upper end of said breathing tube.

5. A submarine breathing device comprising a face mask, a mouthpiece, a breathing tube projecting above said mask and through which air may be admitted, a container for respiratory gas, a three-way valve, a single control element for said valve, said valve being provided with a rotatable core, said core having a shaft concentric with its axis of rotation, an arm extending radially from said shaft, means to connect said mouthpiece, breathing tube and gas container to said three-way valve so that by rotation of the core of said valve the mouthpiece may be connected either to said breathing tube or to said gas container, a plug adapted to close the open end of said breathing tube, spring means normally urging said plug away from the end of said tube, and a wire connecting said plug and said arm, said wire running for a portion of its length within said breathing tube, said arm being positioned on said shaft so that when said core is rotated to connect the mouthpiece to the gas container said plug will be pulled into position to close the open end of said breathing tube.

6. A submarine breathing device comprising a face mask, a mouthpiece, an upwardly extending breathing tube projecting above said mask and through which air may be admitted, a container for respiratory gas, a three-way valve, said valve being provided with a rotatable core, said core having a shaft concentric with its axis of rotation, an arm extending radially from said shaft, means to connect said mouthpiece, breathing tube, and gas container to said three-way valve so that by rotation of the core of said valve the mouthpiece may be connected either to said breathing tube or to said gas container, a spray

shield attached to the upper end of said breathing tube, an opening provided in the lower portion of said spray shield to allow the passage of air into the tube, a float provided with a hole therethrough permitting it to be slidably positioned on said breathing tube below the opening in said spray shield, a portion of said float cooperating with said opening to prevent the entrance of water into said spray shield when the float is submerged, a plug adapted to close the upper end of said breathing tube, spring means normally urging said plug away from said tube, and a wire connecting said plug and said arm, said wire running for a portion of its length within said breathing tube, said arm being positioned on said shaft so that when said core is rotated to connect the mouthpiece to the gas container said plug will be pulled into position to close the upper end of said breathing tube.

7. A submarine breathing device comprising a face mask, a mouthpiece, an upwardly extending breathing tube projecting above said mask and through which air may be admitted, a container for respiratory gas, a lung bag shaped in the form of an inverted truncated pyramid, means to support said lung bag over the chest of the wearer, means to support said respiratory gas container from the bottom of said lung bag, means to conduct gas from said container to said lung bag, a three-way valve, said valve being provided with a rotatable core, said core having a shaft concentric with its axis of rotation, an arm extending radially from said shaft, means to connect said mouthpiece, breathing tube, and lung bag to said three-way valve so that by rotation of the core of said valve the mouthpiece may be connected either to said breathing tube or to said lung bag, a spray shield attached to the upper end of said breathing tube, an opening provided in the lower portion of said spray shield to allow the passage of air into the tube, a float provided with a hole therethrough permitting it to be slidably positioned on said breathing tube below the opening in said spray shield, a portion of said float cooperating with said opening to prevent the entrance of water into said spray shield when the float is submerged, a plug adapted to close the upper end of said breathing tube, spring means normally urging said plug away from said tube, and a wire connecting said plug and said arm, said wire running for a portion of its length within said breathing tube, said arm being positioned on said shaft so that when said core is rotated to connect the mouthpiece to the lung bag the plug will be pulled into position to close the upper end of said breathing tube.
